EMIL C. ROSENCRANZ, OF EVANSVILLE, INDIANA, ASSIGNOR OF ONE-THIRD TO
WILLIAM H. RUMPF, OF EVANSVILLE, INDIANA.

NUT-LOCK WASHER.

1,311,011.

Specification of Letters Patent. Patented July 22, 1919.

Application filed December 15, 1917. Serial No. 207,315.

To all whom it may concern:

Be it known that I, EMIL C. ROSENCRANZ, a citizen of the United States, residing at Evansville, in the county of Vanderburg and 5 State of Indiana, have invented a new and useful Nut-Lock Washer, of which the following is a specification.

The invention relates to a nut lock and more particularly to the class of nut lock 10 washers for use in securing handles, knobs or the like to dressers, chiffonniers, stand drawers or other articles of furniture.

The primary object of the invention is the provision of a nut lock of this character, 15 wherein the nut or nuts employed for securing a handle or knob to the wood structure of an article of furniture will be firmly held against working loose, so that there is no possibility of the handle or knob becoming 20 accidentally detached or removed.

A further object of the invention is the provision of a nut lock of this character which is extremely simple in construction, 25 readily and easily applied, strong, durable, yet light in weight, and inexpensive in manufacture.

With these and other objects in view, the invention consists in the features of construction, combination and arrangement of 30 parts, as will be hereinafter fully described, illustrated in the accompanying drawing, and pointed out in the claim hereunto appended.

In the accompanying drawing:

35 Figure 1 is a fragmentary sectional view through the wood section showing a drawer handle of conventional form applied with the nut locks constructed in accordance with the invention in securing position for the 40 nuts;

Fig. 2 is a fragmentary perspective view showing one of the nut locks in position for embracing the nut and the other nut lock open prior to its embracing the nut;

45 Fig. 3 is an enlarged sectional view through the nut lock;

Fig. 4 is a view similar to Fig. 3, the section being taken at substantially right angles thereto;

50 Fig. 5 is a plan view of the nut lock engaging a nut;

Fig. 6 is a plan view of the nut lock prior to its engagement with the nut;

55 Fig. 7 is an edge elevation of the nut lock;

Fig. 8 is a perspective view of the nut

lock looking toward its side adapted to be fixed to the face of the wood.

Similar reference characters indicate corresponding parts throughout the several views in the drawing.

60

Referring to the drawing in detail, A designates a piece of wood, B a bail constituting a handle which is swingingly pivoted in the eyes C of bolts D which are passed through the wood A, and carry the adjustable nuts E for the fastening of the bolts. The handle B is one of a number of conventional forms of handles for articles of furniture and this form is merely shown for the purpose of illustrating the application of the 70 nut lock washer hereinafter fully described.

65

The nut lock washer comprises a body 10 preferably made from a rectangular blank of relatively thin sheet metal, for example, scrap galvanized iron or tin, although it 75

may be made from any other thin material having the required rigidity but susceptible of being bent, and contains centrally thereof a hole or aperture 11 for receiving the bolt D. The blank has a greater length than 80

width, the opposite side edges being straight, and the upper and lower edges being straight from the side edges inwardly to points where the two sides of a nut will come when placed upon the bolt. At these points, the upper 85

and lower edges are extended outwardly beyond the other two sides of the nut, as indicated at 12, and said extensions are rounded upon the bolt. At these points, the upper 85

and lower edges are extended outwardly beyond the other two sides of the nut, as indicated at 12, and said extensions are rounded at their ends where they join with said straight portions. The straight side edges of 90

the blank combine with the straight upper and lower edges thereof to form bendable tongues 13, the main portions of which are flat while their outer edges are bent outwardly to form lips 14, which are placed in 95

a position to be engaged by a suitable tool for manually bending the tongues about the side faces of the nut, said tongues bending from points where the curved ends of said extension 12 merge into the straight upper 100 and lower edges of the blank.

95

Formed from the body 10 at points on diametrically opposite sides relative to the hole or aperture 11 so as to be in a position to receive direct pressure from the nut are 105

hollow bur-like projections 15 which are preferably produced by the use of a punch driven through the body 10 so that each projection will be circular in contour and the metal displaced by the punch will pro- 110

105

110

vide on said projections a plurality of burs or a ragged tooth edge, thereby assuring a firm biting engagement of the projections in the wood when forced thereinto, on the 5 working of the nut inwardly upon the bolt D against the body 10 of the nut lock, as is clearly illustrated in Figs. 1 and 4 of the drawing. The projections 15 with the ragged edges or burs and the shortness of 10 the same are reinforced by the solid portion of the circular projection so as to give maximum strength to the latter for penetration in the wood A without bending the teeth or burs and also assuring the positive 15 holding of the nut lock securely after the nut has been drawn as tight as possible upon the bolt against the body 10 of said nut lock. When the nut E has been worked home upon the bolt D and the projections 15 have penetrated their full depth into the wood A, a 20 suitable tool, for example, the pliers hereinbefore mentioned are engaged with the lips 14 of the tongues 13 to bend the same outwardly and inwardly against opposite 25 sides of the nut E as shown in Figs. 1, 2, 3 and 5 of the drawing, so that the nut will be securely locked against turning action upon the bolt D, while the engagement of the projections 15 of the body 10 of the nut 30 lock in the wood A will prevent the turning of the nut lock.

The body 10 within the arc of the marginal rounded edges 12 thereof constitutes a working bed for the nut or a turn-table 35 therefor, so that the nut when threaded upon the bolt will act directly upon the body 10 on the inward movement of the nut to positively drive the projections 15 into the wood for the firm fastening of the nut lock 40 washer thereto.

The thin gage metal from which the blank of the nut lock is made makes the latter adaptable for light work, that is, to say, particularly for small nuts and bolts, it being understood that the nut lock is not restricted to the particular adaptation hereinbefore described, as it can be used in any 45

articles made from wood and employing a nut or the like.

From the foregoing, it is thought that the 50 construction and manner of use of the nut lock will be clearly understood, and therefore a more extended explanation has been omitted.

What is claimed is:—

A nut locking washer for use with articles of wood, comprising a substantially rectangular blank of galvanized pliable sheet metal having a central bolt aperture, said blank having a greater length than width, 60 the side edges being straight and the upper and lower edges being straight from the side edges inwardly to points where the two sides of the nut will come, said upper and lower edges being extended outwardly at said 65 points beyond the other two sides of the nut and having the said extensions rounded at their ends where they join with said straight portions, projections formed in the blank by a punch so that each projection will present a plurality of burs to engage a wood surface, said projections being provided at points between the bolt aperture and said extensions so as to be in a position to receive direct pressure from the nut, the straight 70 side edges of the blank combining with the straight upper and lower edges to form bendable tongues the main portions of which are flat, their outer or side edges being bent outwardly to form lips whereby they are in 75 a position to be engaged by a suitable tool for manually bending the tongues about the side faces of the nut, said tongues bending from points where the curved ends of the extension merge into the straight upper 80 and lower edges of the blank.

In testimony that I claim the foregoing as my own, I have hereto affixed my signature in the presence of two witnesses.

EMIL C. ROSENCRANZ.
